(57) **CLAIM**

The ornamental design for a lavatory, as shown and
described.

DESCRIPTION

In preferred embodiment, the nature of this product is as a
plumbing fixture primarily useful for washing the face and
hands of humans.

FIG. 1 is a left, top, front perspective view of a lavatory
embodiment my new design;

FIG. 2 is a front elevational view thereof, the right and left
side elevational views and the rear elevational view all being
identical to the front elevational view shown;

FIG. 3 is a top plan view thereof;

FIG. 4 is a bottom plan view thereof; and,

FIG. 5 is a top plan view of a second embodiment, the front,
rear, right side, and left side elevational views being identical
to that shown in FIG. 2, and the bottom plan view being
identical to that shown in FIG. 4.

The broken line representation of a hole in FIGS. 1, 3, 4, and
5 is for the purpose of illustration only, and forms no part of
the claimed design.
